GARDENING IMPLEMENT

John F. Fielden, Pear Tree Cottage, 21 Victoria St.,
Fleckney, Leicestershire, England

Filed Aug. 3, 1970, Ser. No. 24,259

Claims priority, application Great Britain Feb. 10, 1970

Term of patent 14 years

Int. Cl. D8—01

U.S. Cl. D8—7

FIG. 1 is a front perspective view of a gardening implement, showing my new design,

FIG. 2 is a similar view showing the implement in an open position,

FIG. 3 is a rear view of the implement,

FIG. 4 is a side view of the implement.

I claim:

The ornamental design for a gardening implement, as shown.
